UNITED STATES PATENT OFFICE.

JOSEPH WARREN CUTLER, OF ROCHESTER, NEW YORK.

MAIL CHUTE.

1,413,902.

Specification of Letters Patent. Patented Apr. 25, 1922.

Application filed November 9, 1920. Serial No. 422,921.

To all whom it may concern:

Be it known that I, JOSEPH WARREN CUTLER, a citizen of the United States, residing at Rochester, in the county of Monroe and State of New York, have invented certain new and useful Improvements in Mail Chutes; and I do hereby declare the following to be a full, clear, and exact description of the same, reference being had 10 to the accompanying drawings, forming a part of this specification, and to the reference numerals marked thereon.

My present invention relates to mail chutes employed for conveying letters from 15 the upper portion of a building to the receiving box below, and particularly of the type embodying hinged panels or doors for permitting access to the interior of the chute for cleaning the same or removing 20 stoppages, and it has for its object to provide improved means for effectually securing the doors or panels in closed position and preventing openings or cracks between the panel and the body of the chute, 25 and permitting the manipulation of the panel by the operator from a convenient position, so that he can be assured when leaving the chute that it is perfectly adapted for the conduction of mail matter.

30 This invention consists in special improvements as will be hereinafter more fully described and the novel features pointed out in the claims:

In the accompanying drawings:

35 Figure 1 is a front elevation of the sections of the mail chute between the floor and ceiling, with the intermediate portions broken away;

Figure 2 is a similar view with the section locking plate unlocked and swung open;

Figure 3 is a front elevation with the movable panels or doors of both sections thrown open;

45 Figure 4 is a vertical sectional view on the line A—A of Figure 2;

Figure 5 is a similar view showing the upper movable panel in raised or unlocked position;

50 Figure 6 is a horizontal sectional view on the line B—B of Figure 4;

Figure 7 is a horizontal sectional view on the line C—C of Figure 1;

Figure 8 is a horizontal sectional view

on the line D—D of Figure 4, the lug on 55 the upper panel being omitted, and

Figure 9 is a view of the upper edge of the top panel shown in Figure 5.

Similar reference numerals indicate similar parts in the several figures.

Mail chutes of the type to which my invention relates usually consist of a chute body open preferably at the front, the open side being closed by a plurality of movable panels, said body being composed of a 60 series of superposed sections, the portion between each ceiling and floor being of such length that it can be conveniently handled, two sections usually being employed between these points but a greater 65 number may be used if desired. The section holding devices embody a floor section or casting 1 attached to a suitable backing, an intermediate section or casting 2 arranged above it and in alignment therewith, and an upper frame or casting 3 arranged near the ceiling. 4 indicates the usual sheet metal chute channel sections open at one side, preferably the front, and provided with longitudinally extending double flanges 5 in the sides of the opening, the sections 4 fitting within the frames or castings 1, 2 and 3, as shown in 70 Figure 4, and being capable of being assembled or removed in any suitable manner. The front of the chute consists of 75 movable doors or panels embodying the glass 6 contained in a suitable molding or frame 7 to cooperate with the flanges 5 on the tubular sheet metal section, as shown 80 in Figure 7, the moldings 7 being united at their ends by suitable cross bars or frame members 8, 9, 10 and 11. The panels or doors of the chute are adapted to be moved 85 outwardly to permit free access to the interior of the chute, as shown in Figure 3, being suitably hinged at one side thereof.

In the present instance, the lower panel or the one immediately above the base 1, has its cross bar 8 provided with a pivot pin 100 111 entering a suitable socket formed in the base, and is provided with a downwardly extending flange 12 adapted, when the panel is closed, to extend inside of the top of section 1. This bar 8 is also provided near 105 the hinge with a lug or projection 13 beveled upon its forward side at 14, as shown in Figure 4, and adapted when the panel is

closed to cooperate with the corresponding inclined portion formed in the top of the base casting 1, so that while the lower end of the lug 13 supports the panel, when 5 in the position shown in Figure 3, it will, when the panel is swung upon its hinges, slide down the inclined portion on the base casting and allow the panel to move so that the flange 12 will pass behind 10 the front of the upper portion of the casting 1, this vertical movement of the panel being permitted by the loose connection which the pin 11 has in its socket. The bar or plate 9 at the upper end of the 15 lower panel engages and protects the upper end of the glass front, and is provided at one end with a socket or recess adapted to receive the stationary pintle 16 corresponding to and in line with the pintle 11 in the 20 lower end. This bar 9 is also provided with a lifting handle 17, by means of which the panel can be lifted vertically upon its hinge pintles to disengage the lug 13 at the bottom from the base casting permitting 25 the panel to be swung upon its hinges to open position. The panel can also be bodily removed when desired by lifting the pintle 11 out of its socket and moving it laterally to pass the base casting, sufficient play being allowed between the parts to permit 30 this.

The intermediate bracket or casting 2, arranged between the lower panel just described and the next chute section above it, 35 is formed with a cross bar 18 at the front, the edge of which projects slightly inwardly beyond the lower panel to prevent the lodging of mail matter upon the latter, and also is provided at one end with a lug or boss 19 carrying the pintle pin 16 for the upper and lower panels, and to the outer side of this lug at 15 is hinged a locking bar or plate 20 adapted, when swung to the position in Figure 1, to prevent the swinging movement 40 of the ends of the adjacent swinging panels and cover and prevent the actuation of their operating mechanism, this locking bar 20 being secured in the usual manner by a key lock 21 when in closed position.

50 The upper panel or door is adapted to swing outwardly to the position shown in Figure 3, and also to move vertically on its hinges, the plate 10 constituting its lower member being provided with a hinge member having an aperture to receive the upper end of the pintle 16 as shown in Figure 2, and the upper plate or bar 11 being provided with a pintle 21 entering a corresponding socket or recess at the edge or side of 55 the upper bracket 3 in alinement with the pin 16. The plate or bar 10 is also provided with a lug 22 corresponding to the lug 13 at the lower end of the lower panel, beveled on the front side as shown in Figure 4, and

adapted to rest upon the upper surface of 65 the lug 23, on the bracket 2 when the panel is swung open, but serving to hold the lower end of the panel tightly against the casting or bracket 2 when moved inwardly and downwardly, the inner side of the lug on the 70 front of the latter being beveled for this purpose. The bar 10 is also provided with a lifting handle or hook 123, by means of which the panel may be raised without disengagement from the pintles, this hook, 75 however, being beneath and covered by the bar or plate 20 when in locked position, as shown in Figure 4, to prevent vertical movement as will be understood.

As the upper panel is of considerable 80 length, and its upper end is usually near the ceiling and inaccessible to the operator under ordinary circumstances, it is necessary to employ means for insuring the tight closure of the outer or free edge of the panel when 85 closed, as notwithstanding the greatest of care in construction, such panels will sometimes become slightly twisted. In order to insure this proper closing, I cause the upper edge of the panel that is removed from the hinge to be drawn closely against its seat during the swinging movement in closing, the weight of the panel itself contributing to the result and locking means being incapable of operation until the panel is in 90 proper position. In the present embodiment of the invention, this is accomplished by providing upon the rear side of the upper cross bar 11 a cam flange 26, formed in this instance upon a separate plate 25 and having 100 its lower edge inclined downwardly toward the hinge axis as shown in Figure 3 and also tapered toward the outer free end of the panel, as shown in Figure 9. This flange and the bar 25 are so constructed and arranged that when the panel is closing as soon as the lug 22 at the lower end of the panel drops off its supporting projection 23, the lower edge of the flange 26 drops upon the bar 24, and by the action caused by 105 these relatively inclined surfaces, the upper end of the free edge of the panel is gradually drawn inwardly against the cooperating side wall of the stationary section and held tightly against it, preserving the tight joint 110 necessary in devices of this construction. When the upper panel has moved to its lowermost position, and not until then, the operating handle or some projecting portion of the cross bar 10 is beneath the upper edge 115 of the locking bar 20 which can then be swung over into position and secured by the key lock, thus preventing the unauthorized opening of the chute. The bar 20 being at a convenient height from the floor, the operator is assured when this is movable to engaging position that all parts of the chute 120 are in proper condition for use.

The vertical movement permitted the upper panel when closed is just sufficient to permit the automatic locking referred to, as shown in Figures 4 and 5, but is insufficient to prevent disengagement of the hinge members because its top bar 11 is then beneath flange 29 of the cap piece 30. The upper panel or door can be applied or removed by the relatively vertical movement of the hinge members when it is swung out to the position shown in Figure 3, the upper end being then clear of the flange 29.

While the principal function of the upper closing and locking flange 26 is to insure the secure closure of the outer free edge of the hinged panel, it is desirable that the cam surface be continued from the outer edge toward the hinge a considerable distance in order that the point of contact between the panel and the support 24 may travel outwardly from the hinge toward the free edge as the panel descends to its locked position, the weight of the panel, of course, contributing to this result.

The lower panel might, if desired, be supported by a cam connection at its upper end and secured, as is the upper panel, but in practice this is found to be unnecessary as this portion is usually under the direct control of the operator when manipulating the locking bar 20 and he can at once correct any misplacement or improper operation of the parts which are within his reach.

I claim as my invention:

1. The combination with a mail chute open at one side, of a movable panel adapted to close the opening hinged at one side thereof and also vertically movable, and cam connections between the upper end of the panel and the channel, operating to draw the upper end of the panel into close contact with the side of the channel when it is moved vertically.

2. The combination with a mail chute open at one side, of a movable panel adapted to close the opening, hinged at one side thereof and also movable vertically and a cam connection between the section and the upper end of the movable panel operating to draw the free edge of the panel into close contact with the section when the panel is moved downwardly.

3. The combination with a mail chute open at one side, of a movable panel adapted to close the opening hinged at one side thereof and movable vertically, means for supporting the panel when swung outwardly on its hinges and a cam connection between the upper end of the panel and the chute, serving to draw the free edge of the panel into close contact with the chute when said panel is swung on its hinges toward closed position and after passing off the supporting means.

4. The combination with a mail chute open at the front, of a plurality of superposed panels hinged at the sides of the opening and vertically movable on their hinges, the upper panel having a cam connection at the upper free end with the chute body, operating when said panel is moved vertically to draw its outer free edge against the body, said lower panel engaging the chute body when moved vertically and locking means engaging the proximate ends of said panels and securing them in locked position.

5. The combination with a mail chute open at the front, of a movable panel for closing the opening, hinged at one side and movable vertically, and an inclined bearing and locking ledge between one end of the panel and the chute body serving to support the panel when opened and to draw the edge removed from the hinge into contact with the side of the chute when said panel is moved on its hinges to closed position.

6. The combination with a mail chute open at the front and having a bar at one end of the opening, of a movable panel for closing the opening hinged at one side thereof and also movable vertically on its hinges provided with a supporting ledge adapted to engage the bar and inclined downwardly from the outer edge of the panel toward the hinge thereof.

7. The combination with a mail chute open at the front, of a plurality of movable panels for closing the opening hinged at one side thereof and vertically movable on their hinges, cam connections between said panels and the chute body to draw said panels into close contact with the body when swung to closed position and moved vertically, and a movable bar engaging the ends of adjacent panels for securing them in closed position.

8. The combination with a mail chute open at the front and a ledge at one end of the opening, of a panel hinged at one side of the opening and also vertically movable and provided with a flange adapted to engage behind the ledge on the chute body and cam connections between the panel and body operating upon the vertical movement of the panel to draw the free edge thereof into engagement with the body and position the flange behind the ledge.

9. The combination with a mail chute channel section open at the front and the bracket at one end of the section having the transverse bar, of a hinged and vertically movable panel for closing the front of the chute and provided with a flange for engaging the bar, the engaging edges of the bar and flange being relatively inclined vertically and horizontally to move the panel vertically and laterally into close contact with the channel section when said panel is swung on its hinges to closed position.

10. The combination with a mail chute channel open at the front and supporting brackets at opposite ends, one provided with a cross bar and the other with a supporting projection at one side of the channel, of a vertically movable panel for closing the opening hinged at one side thereof and hav-

ing a portion at one end engaging the supporting projection on one bracket near the hinge and at the other end an inclined cam 10 flange engaging the cross bar to draw the free edge of the panel when relieved from the supporting projection.

JOSEPH WARREN CUTLER.
